UNITED STATES PATENT OFFICE

CYRUS J. BRISTOL, OF DES MOINES, IOWA, ASSIGNOR TO GLOBE MACHINERY & SUPPLY COMPANY, OF DES MOINES, IOWA, A CORPORATION OF IOWA

HYDRAULIC LIFT FOR VEHICLES

Application filed December 15, 1930. Serial No. 502,436.

The object of this invention is to provide an improved vehicle lift of simple, durable and inexpensive construction which is particularly adapted to lift large vehicles such as buses and the like, and to provide a pair of lifting elements, one at each end of the vehicle supporting track; and in connection therewith improved means for connecting the tracks to the lift members whereby sliding and pivotal connections may be maintained between the lift heads and the track members, and at the same time maintain the stability and equilibrium of the track members.

This invention consists in the construction, arrangement and combination of the various parts of the device, whereby the objects contemplated are attained, as herein-after more fully set forth, pointed out in my claim, and illustrated in the accompanying drawing, in which:

Figure 1 shows a side elevation of my improved lift.

Figure 2 shows a top view of one end of the lift.

Figure 3 shows a detail sectional view taken on the line 3-3 of Figure 2.

In the drawing I have used the reference numerals 10 and 11 to indicate upright cylinders spaced apart a considerable distance, and of the ordinary construction adapted to employ oil or similar fluid for operating the piston 12 mounted in each of the cylinders. Each piston carries a lift rod 13 slidably mounted therein.

The upper end of each of the lift rods 13 is provided with a head 14 which is preferably constructed of structural steel, having side members 15 and end members 16. A plate 17 is secured to the top edges of the members 15 and 16, said plate being substantially diamond shaped, as illustrated in Figure 2.

The upper ends of the lift rods 13 are provided with notches or openings 18 for receiving a shaft 19. Each end of the shaft 19 has a downwardly and outwardly extending portion 20 terminating in a horizontally extending portion 21. The members 21 are designed to project through openings 22 in the end members 16.

The head 14 is rigidly connected with the upper end of the member 13 by welding, so that said head and the shaft 19 are permanently fixed to the lift rod. The upper end of the tubular lift rod 13 is provided with a cover plate 23 for closing the end of the lift rod.

Pivots mounted on each of the outwardly extending portions 21 of the shaft 19 is a bar 24 having a slot 25 for receiving the members 21. Each of the bars 24 preferably comprise an I-beam 26 and a pair of plates 27. Said plates are supported between the flanges of said I-beams in the manner clearly illustrated in Figure 3. The slots 25 are in the plates 27 as well as the web of the I-beams 26. Secured to each set of corresponding ends of the bars 24 is a beam 28 mounted parallel with the shaft 19 and of a length substantially equal to the tread of the wheel base of the vehicle to be carried by the lift.

The corresponding end of each set of beams 28 is provided with a channel shaped track 29 having flanges 30 projecting upwardly. The track members are rigidly secured to the beams by suitable rivets 31 or by welding.

By this arrangement it will be seen that the bars 24, the cross beams 28 and the track members 29 form a rigid frame member. Each end of the frame is pivotally connected to a corresponding lift head by means of its corresponding shaft 19, and at the same time provides means whereby one end of the track may be elevated above the other if so desired.

The shaft 19 provides a pivot for permitting the track members to assume an angular position relative to the ground surface.

The slots 25 provide means whereby the shafts may move longitudinally of the track members as one end of the track member is elevated to accommodate the increase in the distance between the pivot centers, and to relieve the lift rods 13 of lateral strain that would otherwise exist. It should be understood, of course, that the lift rod will move upwardly in a vertical line with one lift rod parallel with the other.

On account of the lift head being fixed to the upper end of its corresponding lift rod,

it will be seen that the track members of the supporting frame will be supported against swinging about a central longitudinal axis extending through the upper ends of the lift rods, while means is provided whereby either end of the track may be elevated or lowered with respect to the other, without any great tendency toward the upper ends of the lift rods being pulled together.

10 Suitable means not illustrated herein, but illustrated and described in a co-pending application, is provided for supplying power equally to the pistons 12, or whereby either end of the track may be elevated relative to 15 the other end.

I claim as my invention:

A lift device comprising two track members spaced apart, two lift devices one under each end portion of the track members, each 20 lift device including a vertically movable rod, a head rigidly secured to each rod, a shaft fixed to each head with its ends projecting beyond the head, means for connecting said shafts to the said track members, 25 said means comprising two spaced apart beams one on each side of the head, said beams being rigidly secured to the track members, and two spaced apart bars fixed to said beams formed with longitudinal slots through 30 which the ends of the said shafts are extended, for the purposes stated.

CYRUS J. BRISTOL.
